DESIGN FOR A RUSTIC CHAIR

Luke E. Leonard and Cyril A. Leonard, Utica,
Mich.

Application May 24, 1933. Serial No. 48,203

Term of patent 3½ years

To all whom it may concern:

Be it known that we, LUKE E. LEONARD and CYRIL A. LEONARD, subjects of the Irish Free State and King of Great Britain respectively, residing at Utica, in the county of Macomb and State of Michigan, have invented a new, original, and ornamental Design for a Rustic Chair, of which the following is a specification, reference being had to the accompanying drawing forming part thereof.

Fig. 1 is a front elevation of a rustic chair showing our new design.

Fig. 2 is a side elevation thereof.

Fig. 3 is a rear elevation thereof.

We claim:

The ornamental design for a rustic chair, as shown.

LUKE E. LEONARD.
